ATTORNEYS

UNITED STATES PATENT OFFICE.

HYMAN DELMAN, OF NEW YORK, N. Y.

RECEPTACLE.

Application filed November 7, 1922. Serial No. 599,569.

To all whom it may concern:

Be it known that I, HYMAN DELMAN, a citizen of the United States, and a resident of the city of New York, borough of Manhattan, in the county and State of New York, have invented a new and Improved Receptacle, of which the following is a full, clear, and exact description.

This invention relates to improvements in receptacles, and has particular reference to a hand bag or the like.

An object of the invention is to reinforce the open end of the body portion of a receptacle and the closure for said open end by providing novel cooperating frame members which are connected in such manner as to prevent the movement of the closure to its open position beyond a predetermined extent with respect to the body portion.

Another object is to provide a reinforcing frame of simple and durable construction which, when applied to a receptacle, will be effective in carrying out the purpose for which it is designed.

The above and other objects will appear more clearly from the following detail description, when taken in connection with the accompanying drawing, which illustrates a preferred embodiment of the inventive idea.

In the drawing—

Figure 1 is a perspective view of a receptacle, such as a hand bag, showing the invention applied thereto;

Figure 2 is a detail perspective view of the connection between the cooperating frame members showing the same in partially opened position;

Figure 3 is a fragmentary side elevation of the frame members showing the same in closed position;

Figure 4 is a view similar to Figure 3 taken at right angles thereto;

Figure 5 is a section on the line 5—5 of Figure 3;

Figure 6 is a view similar to Figure 3 showing the frame members in opened position; and

Figure 7 is a section on the line 7—7 of Figure 1.

Referring more particularly to the drawing, the numeral 8 indicates the body portion of a hand bag or other receptacle, which is of rectangular formation and which has an open end designed to be closed by the

closure 9, having a pivotal movement with respect to the body portion.

In order to connect the closure 9 with the body portion 8, the invention contemplates the provision of a pair of cooperating frame members 10 and 11 which, when in position on the body portion and closure respectively, reinforce the edges of said parts and prevent breaking or distortion thereof due to constant use of the receptacle. The frame members 10 and 11 are preferably formed of sheet metal and each includes three sides designed respectively to engage the edges of the ends and front of the body portion and the end and front edges of the closure 9. The frame 10 includes the side flanges 12 disposed in parallel relation to form a substantially U shaped structure in cross section and arranged a sufficient distance apart to snugly receive the edges of the body portion surrounding the open end thereof on three sides of the same and, if desired, any suitable means, such as rivets (not shown), may be employed to secure the frame in position on the body portion.

The frame 11 also includes the side flanges 13 to form a structure substantially U shaped in cross section and said flanges are so spaced as to snugly receive the three edges of the closure 9. When the frames are in position on the body portion and closure, the side flanges of the respective frames are disposed transversely to each other so that the inner side flanges of the frame 11 will engage the portions of the frame 10 joining the side flanges 12 thereof when the closure is in its closing position.

The frames 10 and 11 are hingedly connected to each other at their extremities by preferably providing the respective frames with flat disk-like plates 14 and 15 having adjacent faces in engagement with each other and secured together by a suitable rivet 16 about which the frames have a pivotal movement. Means are provided in connection with the plates 14 and 15 for preventing movement of the closure 9 to an open position beyond a predetermined extent so that the closure may be supported in a definite position without the necessity of holding the same in such position. This means as shown consists of a stop flange 17 formed upon the periphery of the plate 15 at a point remote from its connection with

the frame 11, which flange is bent to engage the face of the plate 14 opposite to that which is engaged by the plate 15 so as to, in effect, provide a guide for the plates 5 when the frames are moved about the pivots 16. The portion of the frame 10 contiguous to the plate 14 thereof is provided with an offset 18 arranged in the path of movement of the stop flange 17 as the same rotates about 10 the pivot 16, so that when the frame 11 is moved to its open position, an edge of said flange 17 will engage the offset 18 and thereby prevent further movement of the closure toward its open position.

15 A suitable lock (not shown) of any desired construction may be utilized to maintain the closure 9 in closing position with respect to the body portion 8.

What is claimed is:

20 1. In a receptacle, the combination with a body portion having an open end and a closure for said end; of a frame including opposed flanges for receiving therebetween edges of said body portion surrounding said

25 opening, and a second frame connected to the first named frame and also including flanges for receiving therebetween edges of said closure, the flanges of the respective frames being disposed transversely relative to each other.

30 2. In a receptacle, the combination with a body portion having an open end and a closure for said end; of a frame including opposed flanges for receiving therebetween edges of said body portion surrounding said

35 opening, a second frame connected to the first named frame and also including flanges for receiving therebetween edges of said closure, the flanges of the respective frames being disposed transversely relative to each

40 other, and means carried by one of said

frames and engageable with a portion of the other frame for limiting the movement of the closure toward its open position.

3. In a receptacle, the combination with 45 a body portion having an open end and a closure for said end; of a frame including opposed flanges for receiving therebetween edges of said body portion surrounding said opening, a second frame connected to the 50 first named frame and also including flanges for receiving therebetween edges of said closure, the flanges of the respective frames being disposed transversely relative to each other, one of said frames having an offset 55 portion adjacent its point of connection with the other frame, and a stop flange forming a part of said other frame and embracing a portion thereof for contacting said offset portion to limit the movement of said closure toward its open position.

4. In a receptacle, the combination with 60 a body portion having an open end and a closure for said end; of a frame including opposed flanges for receiving therebetween 65 edges of said body portion surrounding said opening, a second frame connected to the first named frame and also including flanges for receiving therebetween edges of said closure, the flanges of the respective frames 70 being disposed transversely relative to each other, said frames having contacting plates at their extremities pivotally connected to each other, one of the plates at each extremity being provided with an offset portion, and a stop flange formed upon the adjacent plate and embracing a portion of the other plate and engageable with said offset portion to limit the movement of the closure toward its open position.

HYMAN DELMAN.
